UNITED STATES PATENT OFFICE.

JOHN D. MORGAN, OF SUMMIT, NEW JERSEY.

TYPE-CASTING MACHINE.

1,293,511.

Specification of Letters Patent.

Patented Feb. 4, 1919.

Application filed March 20, 1917. Serial No. 155,976.

To all whom it may concern:

Be it known that I, JOHN D. MORGAN, a citizen of the United States, residing at Summit, in the county of Union and State 5 of New Jersey, have invented certain new and useful Improvements in Type-Casting Machines, of which the following is a specification.

The invention relates to typographic composing machines, and more especially to machines for casting types a letter or character at a time with interverbal quads or spaces so proportioned as to form justified lines.

Objects and advantages of the invention 15 will be set forth in part hereinafter, and in part will be obvious herefrom, the same being attained and realized through the instrumentalities and combinations pointed out in the appended claims.

20 The invention consists in the novel parts, constructions, arrangements, combinations and improvements herein shown and described.

The accompanying drawings herein referred to, and constituting a part hereof, illustrate one embodiment of the invention, and together with the description serve to explain the principles thereof.

Of the drawings:

25 Figure 1 is a front elevation of a machine built in accordance with the principles of the invention;

Fig. 2 is an end elevation, looking at Fig. 1 from the right;

30 Fig. 3 is an end elevation, looking at Fig. 1 from the left, with the drive and frame removed, and the shafts and certain other parts shown in section;

Fig. 4 is a top plan corresponding to 35 Fig. 1;

Fig. 5 is a transverse vertical section, on an enlarged scale, with certain parts omitted, substantially on the line A—B of Fig. 1, looking in the direction of the arrows;

40 Fig. 6 is a transverse vertical section, also on an enlarged scale, taken substantially on the line C—D of Fig. 2;

Fig. 7 is a fragmentary, detail elevation, on an enlarged scale, of the stop cylinder for 45 locating the type disk to discharge the selected cast types;

Fig. 8 is a fragmentary detail, on an enlarged scale, of the device for restoring the stop levers after they have stopped the 50 cylinder;

Fig. 9 is a diagrammatic view of the

mechanism and connections for feeding the controller strip, restoring the stop levers, and associated mechanisms;

Figs. 10 and 11 are fragmentary details 60 of the circuit controlling devices;

Fig. 12 is a fragmentary, sectional detail of a removable type or character matrix face;

Fig. 13 is a fragmentary view, partly in 65 section, and partly diagrammatic, of a gate for the types at the discharge point;

Fig. 14 is a similar view to Fig. 13 showing a shifting or selecting mechanism for a plurality of fonts or faces in connection with 70 a type gate; and

Fig. 15 is a fragmentary sectional view of one form of type selecting device.

Referring to the accompanying drawings, 75 illustrating by way of example one embodiment of the invention, a traveling series of character casting devices are presented successively at the casting and delivery positions. In said embodiment, a rotating carrier is provided with a plurality of chambers for casting the various desired characters, these chambers passing from the molten metal supply, where the empty chambers are charged, to a discharging position, where the cast types are discharged in justified lines. 80

In accordance with certain features of the invention, the carrier for the cast types is caused to selectively and successively discharge or eject at the discharging point or 85 composing point, the cast types in the sequence or selection required for the desired composition, the word spaces being of proper size to justify the lines. Such selective discharging of the types is preferably effected by stopping the carrier successively at the discharge point under the selective action of a controller. Such controller may be of various specific form or character, and comprises preferably a perforated sheet. Such sheet may likewise vary 90 in its characteristics, but an example of a suitable sheet is one wherein a plurality of character selecting perforations occur in a single transverse line of the controller sheet or strip.

100 In such embodied form, the carrier 1 is shown of circular, and general disk-like, form and is supported and rotated by a shaft 2. Shaft 2 is successively rotated and stopped to discharge and compose the cast 105 types. In the carrier 1, and preferably radially disposed and opening onto the pe-

riphery of the carrier, are a series of chambers 3, each for the purpose of casting a particular type, space-quads or character. At the bottom of the respective chambers 5 are the type faces. These type faces may be removable, if desired, and are so shown in Fig. 12. The type faces in this figure are formed respectively, in removable pieces 5, which pieces are held in position in any suitable manner, as by screws 6.

In accordance with certain features of the invention, the pot 7 for the molten metal is in direct communication or connection with the chambers 3 in disk 1, whereby any of the 15 type chambers 3 which have become empty by being discharged at the discharging or composing station, are filled with molten metal as they pass the pot 7. More particularly as embodied, the metal pot may be of 20 any suitable or convenient form and may be in whole or in part under pressure. As shown, a piston or weight 9 is employed for this purpose. The heating devices for pot 7 are not shown, but may be of any suitable 25 or approved form.

The bottom of the pot 7 is open at 8 and is closed by the periphery of the wheel 1, by any suitable form of joint. As shown, the periphery of wheel 1 is beveled at either 30 side of the type chambers 3, and the bottom of the melting pot is correspondingly beveled. The connection or joint between the pot 7 and wheel 1, is adjustable and for this purpose, as embodied, there are provided 35 regulating screws 12 threaded into lugs or plates 13 on, or fixed to, the pot, and bearing on surfaces on the machine frame.

Bearing on the periphery of wheel 1 is a stationary retaining ring 14, mounted on the 40 machine frame, and extending, preferably continuously, about the periphery and closing the outer ends of the type chambers 3 except when they are at the pot or at the discharge point.

45 In the present preferred form, a stationary, discontinuous ring shaped or circular plate 16 forms one side of the type-casting chambers, the ring setting into or against the wheel 1, and encircling shaft 2 and being 50 bolted to the machine frame, as will be seen from Figs. 1 and 6. Suitable means will be provided when needed to permit air leakage or escape from a type chamber at the casting point, so as to secure solid type bodies. Such means may be of any suitable 55 form, and as embodied, the ring or plate 16 is jointed or articulated to permit air leakage at the casting point, while preventing metal leakage, and such a joint or articulation 60 is shown in Fig. 6. The plate or ring 16 is discontinuous or cut away, at the discharge point 17, as will be seen from Fig. 6, to facilitate the discharge or composing of the selected types.

65 Means may be provided for facilitating

the discharge of the selected types from the casting chambers, and as embodied one or more resilient, rotating arms or disks 20 operate in the recess in ring 16, and force the types outwardly into the channel 18, which 70 directs it into the line in the galley.

The galley and the controlling and co-operating mechanism whereby the types for a line are received and the galley fed forward to receive the next line are not shown, 75 but may be of any suitable form.

The manner of operation of the mechanism already described is substantially as follows:—

As the type casting chambers 3 pass beneath the pot 7, they are filled with metal and the types are cast. As the wheel rotates, the casting chambers 3 pass successively from the pot 7, and their outer ends are then closed by the ring 14, and the bottom ends 80 of the types are thereby formed and smoothed. In the preferred form, if the wheel continues its rotation, the types are not discharged at the composing point 17, but if the wheel is stopped, the particular 85 type then at the discharge point is ejected and passes into the line in the galley. As the type chambers 3 pass onward, they again pass beneath the metal pot 7. If a type 90 has been discharged from a chamber, a new type is cast therein from the metal in the pot 7, but if not, the type chamber being already 95 full, there is, of course, no casting.

Means are provided by the invention for intermittently causing the discharge of the 100 composed type in a selected sequence to produce a given composition, as perforated or otherwise indicated in a controller or composition strip α , which is usually preliminarily prepared to determine and apportion 105 the size of the interverbal spaces or quads, to produce the justified lines. As embodied, upon shaft 2 is fixed a stop cylinder 30, provided with stops 51 disposed over its surface 110 to correspond to the locations of the type casting chambers 3 in a wheel 1. With cylinder 30 co-operate stop devices or mechanisms governed or operated by the composing or controller strip α . Fixed to shaft 2 is 115 a suitable drive tending to rotate the shaft and therewith wheel 1, but permitting them to be stopped from time to time by the stop cylinder mechanism. Said drive, as embodied, comprises a friction clutch 31 and a belt and pulley drive 32.

Co-operating with stop cylinder 30 is a bank or series of levers 33, each of which levers is supported by a slot 34 therein, through which passes a rod 35. Each of the levers 33 has a stop lug 50 thereon adapted to co-operate with one of the stops 51 in the stop cylinder. The levers 33 are impelled forwardly (to the right in Fig. 3) and downwardly in a suitable manner, as by a corresponding series of springs 36 which ex- 120 125 130

tend between an arm 37 on each of the respective levers 33 and the frame piece 38.

At their forward ends the levers 33 have, respectively, a flexible connection 39 with a corresponding bank or series of controller strip levers 40, the levers 33 resting upon the corresponding levers 40, but there is some relative movement therebetween, as will be later explained. The levers 40 are pivoted, respectively, on a rod 41 supported by the machine frame, and are impelled downwardly by a series of springs 42. The levers 40 have each a downwardly extending detector finger 43, adapted to coöperate with a perforation in the controller strip α . Beneath the detector fingers 43 of the levers 40 is located a cylinder 44, journaled in the machine frame, and over which cylinder the controller strip α passes. The cylinder 44 is constructed to permit the dropping of a lever 40 and therewith of the corresponding lever 33 when the detector finger 43 of the particular lever 40 meets a perforation in the controller strip α . As embodied, the cylinder 44 has in its periphery a series of holes 45, to permit the downward dropping of the detector fingers or levers as already described.

Also the cylinder 44 is provided with means for insuring an accurate and exact feed of the controller strip α . The cylinder 44 has also, at either end thereof, a series of sprocket teeth 46, which sprocket teeth coöperate with sprocket holes 47 in the controller strip α . The controller strip is further guided by a pair of rollers 48 located at either end of the cylinder 44, and straddling the sprocket teeth 46 at either side of the controller strip as it comes on. As the controller strip leaves the cylinder 44, it is similarly guided by a similar pair of guide rollers 49.

Means for restoring the stop levers 33, and the coöperating controller strip levers 40 are provided, and in accordance with certain features of the invention, said means operate to restore the different levers individually or separately, when a plurality of character perforations for selecting successive cast characters occur on a single transverse line of the controller strip α . By this arrangement, a plurality of cast types may be ejected from the type wheel or disk and set up in the galley on a single rotation of the type wheel. This is done when a plurality of sequential characters in a composition are found in the same succession or order, although not necessarily in sequence or proximate order in the type disk, the type disk in such case making only a part of a rotation between stops.

In the embodied form of such means, there is mounted on the machine frame a bar 55 which extends across the tails of the levers 33. As the bar moves downwardly, trans-

versely or edgewise, it will engage the tails of any of the levers 33 when they are in the retracted position, as is the case when the detent on any lever has engaged with its stop 50 in the stop cylinder 30 (that is, the lever has been moved to the left in Fig. 3). The bar 55 in its transverse movement will pass clear of the tails of the levers 33 when the levers are free from their stops on the stop cylinder 30, at which time they are drawn to the right in Fig. 3 by the corresponding spring 36. The bar 55 is suspended upon rods 56 and 57, which constitute, or are connected to, the cores of solenoids 58 and 59, which solenoids are mounted on the frame of the machine. Springs 60 and 61 act between the tops of the solenoids and collars on the upper ends of the rods to hold the bar 55 in elevated position. Solenoids 58 and 59 are in a circuit 52', which circuit is controlled either directly or through a suitable relay, in a well known manner, by contacts 53 which are either closed or actuated by a discharged type.

The manner of operation of the mechanism just described, is substantially as follows:—

The controller strip α may be assumed to have no perforations therein, and at such time the detector fingers 43 (Figs. 2 and 3) will ride upon the surface of the controller strip and levers 40 will be in the elevated position. In such position each lever 40 holds its coöperating lever 33 sufficiently high that the stop lug 50 thereon is clear of the corresponding stop or depression 51 in the cylinder 30. At such time each spring 36 holds its lever 33 in the forward position (toward the right in Fig. 3) and the left hand end of the slot 34 will be against the rod 35. When the detector finger 43 of any one of the controller strip levers 40 finds a corresponding perforation in the controller strip α , the lever drops downwardly under the impulsion of its spring 42, and the corresponding lever 33 also drops downwardly, under the action of its spring 36, thereby bringing its stop lug 50 to rest upon the surface of the rotating stop cylinder 30. When the corresponding stop or depression 51 in the stop cylinder 30 engages the lug 50, lever 33 is thereby pushed backwardly, against the action of its spring 36, and the rear end of the lever comes to rest against the member 52 on the machine frame. Thus stop cylinder 30, shaft 2, and type disk 1, are precisely located so as to discharge the selected type into the orifice 18.

As the type is discharged, the solenoids 58 and 59 are energized, and the bar 55 in descending will depress the rear end of the particular lever 33, which is engaged with the stop cylinder 30, as just described. The detent 50 of that lever is thereby lifted out of the stop 51 in the cylinder, and its spring 36 will draw the lever forward so that its stop lug 50 will then rest upon the sur-

face of the cylinder ahead of its stop 51 with which it had just been engaged. The stop 51 thus cannot engage the lug 50 until the next succeeding revolution of the cylinder 30. Thus, a series of the levers 33 may be operated in succession to stop the cylinder 30 (and therewith the type wheel 1) a plurality of times during a single revolution of the type wheel.

10 Means are provided for feeding forward the controller strip one degree, or the space between one transverse line of perforations and the next, after all the perforations in a transverse line have been recognized or have 15 successively positioned the stop cylinder. In the embodied form of such means, there is provided at one end of the controller cylinder 44 a ratchet wheel 65, fast on the shaft 66 of the cylinder 44. Coöperating 20 with ratchet wheel 65 is a pawl 67, which pawl is pivoted on a lever 68, controlled by a spring 69. Lever 68 is fixed to a shaft 70, which extends parallel to cylinder 44, and which has at the other end thereof a 25 corresponding lever arm. From each of said levers, respectively, there extend upwardly pivotally connected rods 71, these rods having at their upper ends a horizontal cross bar 72, which bar lies just beneath the series 30 or bank of levers 40.

At the other end of lever 68 is an armature 73 of a magnet 74, which magnet is in a circuit 75. Circuit 75 has in one branch thereof a contact 76, which is continually 35 in circuit with the ring 77 on shaft 2. At a selected point in the rotation of type disk 1, which may be called the initial point, is a contact 78 in the other branch of the circuit 75. Fixed to shaft 2 is an arm or disk 40 79 adapted to close the circuit 75 when the particular point in the rotation of disk 1 is reached. Thus when the rotation of disk 1 is completed and the number of perforations 45 on one transverse line of the controller strip α has been recognized or exhausted, the magnet 74 is energized, rod 72 is lifted, and therewith the bank of levers 40 are lifted clear of the controller strip, and the pawl 50 and ratchet 65, 67 feed the controller strip forward the space of one transverse line.

A safety lock to prevent any rotation of the stop cylinder 30 during this movement may also be provided, and in the embodied form, a ratchet wheel 89 is fixed on the shaft 55 51, and has coöperating therewith a pawl 80 held off by a spring 81. Pawl lever 80 has fixed to the other end thereof the armature 82 of a magnet 83 located in the circuit 75. Magnet 83 thus throws in pawl 80 to lock 60 the stop cylinder during the feeding of the controller strip.

A suitable device may be provided for breaking the circuit 75 to return pawl 67 and unlock detent 80 from cylinder 30, so 65 that the machine will start on its next cycle.

As embodied (Fig. 10) the contact bearing disk 79 has thereon a lug 84 of insulating material, and the terminal of circuit 75 is a spring plate 85. Thus when lug 84 engages with spring 85 (see Fig. 11), the circuit is broken, the pawl 67 retracts ready for the next forward feed and detent 80 retracts, and cylinder 30 is free to rotate under the impulsion of its drive.

It may be advisable in certain cases to 75 provide a type gate at the discharge point 17, although usually the types will remain in place and pass the discharge point without the necessity of the gate. In Fig. 13 of the drawings, one embodiment of a gate mechanism is illustrated, the gate being withdrawn each time the stop cylinder 30 comes to rest and a type to be selected and discharged is presented at the discharge point. 85

As embodied, a gate 90 is slidably mounted just below the type disk 1, and connected to the gate by a pivoted rod 91 is a lever having an arm 92, which lever arm is pivoted at 89 upon a bracket 96 on the machine frame. The lever has also an arm 93, between which arm and the bracket 96 is a spring 94, which acts to hold a stop 95 against the bracket, thereby holding the gate 90 in the closed position at the discharge orifice. 90

The core 97 of a solenoid 98 is pivotally connected to the lever arm 92, the solenoid being energized and deenergized in harmony with the movement of the stop cylinder 30. For this purpose the solenoid 98 has the branch 99 of its circuit connected to a contact piece 101 carried upon the stop 52 on the machine frame. The branch 100 of the solenoid circuit extends to a coöperating contact piece carried upon a lever arm 102, pivoted at 103 upon the frame member 52. The other arm of the lever 102 is part of, or is connected to a plate 104, which plate extends along beneath the stop member 52 past the bank of keys 33, the plate 104 being likewise pivotally supported at its other end. The stop levers 33, in this case, are provided with extensions 105, respectively, whereby when a stop lever 33 115 is moved backwardly against the stop plate 52, the extension 105 engages plate 104, thereby closing the solenoid circuit at 101 and 102, and thus drawing the gate 90 to the open position (to the left in Fig. 13) 120 to permit the discharge of the selected type γ .

In accordance with one feature of the invention, selective mechanism for different type fonts or faces, or cases are provided. 125

In accordance with one feature of the invention, such selective mechanism is automatically operated by the controller. Thus a perforation will be encountered in the controller calling for a particular character, say 130

for instance, the letter "a" and this would cause the mechanism to select or discharge a roman, lower case letter. If at the same time an auxiliary perforation is encountered 5 at the proper point in the controller, the letter "a" will still be selected or discharged, but it would be a lower case italic if desired, or it might be an upper case roman or italic, or otherwise varied in accordance with the 10 location of the perforation and the organization of the machine.

In such case, the type disk 1^a may be provided with a plurality of casting chambers for the same type or character but for different 15 fonts, or faces, or cases, or for arabic or roman characters, or otherwise. In Fig. 14, of the drawings one embodiment is illustrated of such a selective mechanism in connection with a type gate. Therein a sliding 20 block or gate 110 is mounted just beneath the type disk 1 and having therein a discharge orifice 111, adapted to pass into alinement or registry with either type chamber *y* or *z*, according to the particular font, or face, or 25 case, desired.

The gate 110 is pivotally connected by a rod 112 to a T-lever having an arm 113, pivoted at 114 upon a bracket 115 carried upon the machine frame. The lever has below 30 two oppositely arranged, laterally extending arms 116 and 117. Beneath these arms, respectively, are springs 118 and 119, balanced to maintain the orifice 111 centrally between the type chambers in the type disk 35 1, the gate 110 at either side of the orifice 111 serving to close both series of type chambers and retain the types *y* and *z* therein.

A solenoid 120 has its core connected to 40 lever arm 116, and a solenoid 121 has its core connected to the lever arm 117, and connections or devices are provided whereby a perforation in the controller will selectively energize either of these solenoids. Thereby 45 gate 110 is moved either to the right or to the left, and thereby permitting either the type *y* or the type *z* to be selected or discharged, while preventing the other of the said types from being selected, and retaining 50 it within the type disk 1.

In the embodied form of the mechanism, in the bank of levers 40 is a lever 40^a having beyond its pivot point a double arm switch 122, 123, which is in the branch 100 of the 55 solenoid circuit. Said switch coöperates with either one of two contact points 124 and 125, connecting, respectively, to the two solenoids 120 and 121. Thus if no perforation is present, the lever 40^a is in the up position (shown in Fig. 14), and the circuit is closed at the contact 124, and in such case the solenoid 121 would be energized upon the circuit being closed at contacts 101, 102 (Fig. 13) and type *y* would be selected (Fig. 60 14). When lever 40^a is in the down posi-

tion, due to the presence of a perforation in the controller strip *x*, the circuit will be closed at the contact point 125, and upon the closing of the circuit at 101, 102, the solenoid 120 will be energized and the type *z* 70 would be selected.

In Fig. 15 of the drawings, the pivoted rod 112 on the lever 113 operates selectively type ejectors. A type ejector 126 is pivoted at 127, and has a downwardly extending 75 arm 128, pivoted to the rod 112. Another type ejector 129 is pivoted at 130 and has a downwardly extending arm 131, pivoted to the rod 112. When lever 113 is rocked to the left, ejector 126 will eject type *z*, 80 and when lever 113 is rocked to the right, ejector 129 will eject type *y*. Such a mechanism may be used with or without the gate shown in Fig. 14, or other equivalent device. 85

The justified lines are secured by proper selection of the quads or interverbal spaces by the controller sheet. Certain of the type casting chambers 3 cast quads or interverbal spaces of various unit widths. That is, one 90 chamber will cast a quad two units wide, and another chamber will cast a quad four units wide, there being sufficient quads of varying unit widths to effect the justification of any possible line. The machine which 95 makes the controller strip has a justifying mechanism, which perforates the strip to select quads or interverbal spaces of the proper size to justify the line. As the present machine coöperates with the controller, 100 quads of the proper size will be selected and delivered to the line at the interverbal spaces to effect the justification.

It will be understood from all the foregoing that a machine has been provided embodying the objects and advantages herein set forth, together with other objects and advantages which in part will be obvious herefrom and in part may be learned by practice with the invention. It will be further understood that changes may be made from the precise mechanism shown and described without departing from the principles of the invention and without sacrificing its chief advantages. 110

What I claim as my invention and desire 115 to secure by Letters Patent is:—

1. A type casting machine including in combination a traveling carrier having type casting chambers therein, a molten metal receptacle through the lower part of which the carrier travels to present empty chambers to be filled by the molten metal to cast types, and means for selectively ejecting such of the cast types as are required in 120 making a composition. 125

2. A type casting machine including in combination a rotatable carrier having a circular series of type casting chambers therein, a molten metal receptacle through 130

the lower part of which the carrier rotates to present empty chambers to be filled by the molten metal to cast types, and means for selectively ejecting such of the cast types as are required in making a composition.

3. A type casting machine including in combination a rotatable carrier having a series of type casting chambers formed in its periphery, a molten metal receptacle through the lower part of which the periphery of the carrier travels to present empty chambers to be filled by the molten metal to cast types, and means for selectively ejecting such of the cast types as are required in making a composition.

4. A type casting machine including in combination a traveling carrier having type casting chambers therein, a molten metal receptacle through the lower part of which the carrier travels to present empty chambers to be filled by the molten metal to cast types, and means for selectively stopping the carrier with desired type chambers sequentially at a composing point, to form a composition from the cast types.

5. A type casting machine including in combination a rotatable carrier having a circular series of type casting chambers therein, a molten metal receptacle through the lower part of which the carrier rotates to present empty chambers to be filled by the molten metal to cast types, and means for selectively stopping the carrier with desired type chambers sequentially at a composing point, to form a composition from the cast types.

6. A type casting machine including in combination a traveling carrier having type casting chambers therein, a molten metal receptacle through the lower part of which the carrier travels to present empty chambers to be filled by the molten metal to cast types, and means, including a previously prepared controller strip, for selectively ejecting such of the cast types as are required in making a composition.

7. A type casting machine including in combination a rotatable carrier having a circular series of type casting chambers therein, a molten metal receptacle through the lower part of which the carrier rotates to present empty chambers to be filled by the molten metal to cast types, and means, including a previously prepared controller strip, for selectively ejecting such of the cast types as are required in making a composition.

8. A type casting machine including in combination a traveling carrier having type casting chambers therein, a molten metal receptacle through the lower part of which the carrier travels to present empty chambers to be filled by the molten metal to cast types, and means, including a previously prepared

controller strip, for successively stopping the carrier with desired type chambers sequentially at a composing point, to form a composition from the cast types.

9. A type casting machine including in combination a rotatable carrier having a circular series of type casting chambers therein, a molten metal receptacle through the lower part of which the carrier rotates to present empty chambers to be filled by the molten metal to cast types, and means, including a previously prepared controller strip, for selectively stopping the carrier with desired type chambers sequentially at a composing point, to form a composition from the cast types.

10. A type casting machine including in combination a traveling carrier having a series of type casting chambers therein, means for supplying molten metal to the empty chambers to cast types, and means including a previously prepared controller for successively selecting and ejecting the types and interverbal spaces required to form justified composed matter.

11. A type casting machine including in combination a rotatable type carrier having a circular series of type casting chambers therein, means for supplying molten metal to the empty chambers to cast types, and means including a previously prepared controller for successively selecting and ejecting the types required to form a composition.

12. A type casting machine including in combination a traveling carrier having a series of type casting chambers therein, means for supplying molten metal to the empty chambers to cast types, and means including a previously prepared controller for successively stopping the carrier with desired types sequentially at a composing point to form a composition.

13. A type casting machine including in combination a rotatable type carrier having a circular series of type casting chambers therein, means for supplying molten metal to the empty chambers to cast types, and means including a previously prepared controller for successively stopping the carrier with desired types sequentially at a composing point to form a composition.

14. A type casting machine including in combination a molten metal container having an opening therein, a carrier having type chambers therein, the type carrier closing said opening, and the container and carrier having relative movement whereby the type chambers are presented at the opening to be filled with metal to cast types, and means controlled by a controller device representing a composition for selecting the types in the sequence of the composition.

15. A type casting machine including in combination a molten metal container hav-

- ing an opening therein, a carrier having type chambers therein, the type carrier closing said opening, the container and carrier having relative movement whereby the type chambers are presented at the opening to be filled with metal to cast types, and a member engaging the face of the carrier adjacent to said opening to form and smooth the bottoms of the cast types.
- 10 16. A type casting machine including in combination a molten metal container having an opening therein, a rotatable carrier having a circular series of type chambers therein, the type carrier closing said opening, and the container and carrier having relative movement whereby the type chambers are presented at the opening to be filled with metal to cast types, and means controlled by a controller device representing a composition for selecting the types in the sequence of the composition.
- 15 17. A type casting machine including in combination a molten metal container having an opening therein, a rotatable carrier having a circular series of type chambers therein, the type carrier closing said opening, and the container and carrier having relative movement whereby the type chambers are presented at the opening to be filled with metal to cast types, and a member having an arcuate surface engaging the face of the carrier adjacent to said opening to form and smooth the bottoms of the cast types.
- 20 18. A type casting machine including in combination a molten metal container having an opening at its bottom, a circular rotatable carrier having a series of type chambers in its periphery, the periphery of the carrier closing said opening in the container, the carrier and container being relatively movable, and means for removing the cast type from the carrier to form a composition, and means controlled by a controller device representing a composition for selecting the types in the sequence of the composition.
- 25 19. A type casting machine including in combination a molten metal container having an opening at its bottom, a circular rotatable carrier having a series of type chambers in its periphery, the periphery of the carrier closing said opening in the container, the carrier and container being relatively movable, and an arcuate member engaging the periphery of the carrier adjacent to said opening to form and smooth the bottoms of the cast types.
- 30 20. A type casting machine including in combination a traveling carrier having type chambers therein, means for supplying molten metal to the type chambers, a gate for the type chambers at the composing point, and means for opening said gate to permit the passage of an ejected type.
- 35 21. A type casting machine including in combination a traveling carrier having type chambers therein, means for supplying molten metal to the type chambers, a previously prepared controller for ejecting selectively desired types for a composition, a gate at the composing point, and means opening the gate successively to permit the passage of the ejected types.
- 40 22. A type casting machine including in combination a type carrier having series of type casting chambers therein, the various characters being represented in different faces or cases, or the like, and previously prepared controller means for selecting desired characters in proper sequence to form a composition and of the particular face or case desired.
- 45 23. A type casting machine including in combination a type carrier having series of type casting chambers therein, the various characters being represented in different faces or cases, or the like, constituting an aligned group and automatic means, including a previously prepared controller sheet, for selecting desired characters to form a composition and of the particular face or case desired from the group.
- 50 24. A type casting machine including in combination a type carrier having series of type casting chambers therein, the various characters being represented in different faces or cases, or the like, and automatic means, including a gate selectively releasing the desired case or face, for selecting desired characters to form a composition and of the particular face or case desired.
- 55 25. The process of casting types and rendering them into a composition, which comprises progressing a series of type chambers through liquid type metal to cast types in the type chambers, and selectively removing such cast types as are required in sequence for a composition, permitting the filled and empty chambers to again pass through the liquid type metal, the empty chambers being thereby refilled, and continuing the selective process on successive travels of the type carrier, each time taking such types as are required in sequence for the composition.
- 60 26. A type casting machine including in combination a traveling type carrier having a plurality of type casting chambers therein, means for supplying molten metal to empty chambers, pressure means for forcing the metal thereinto, and a selecting means including a previously prepared controller for selecting the cast types in the sequence for a composition represented by the controller.
- 65 27. A type casting machine including in combination a traveling type carrier having a plurality of type casting chambers therein, having air escape means, means for

supplying molten metal to empty chambers, and a selecting means including a previously prepared controller for selecting the cast types in the sequence for a composition represented by the controller.

28. A type casting machine including in combination a series of traveling chambers representing type characters and interverbal quads of various widths, and controller 10 operated means for selecting the types in

the sequence required for a composition and therewith successive quads to constitute justified lines.

In testimony whereof, I have signed my name to this specification, in the presence of 15 two subscribing witnesses.

JOHN D. MORGAN.
